A. HENDRICH

THERMOS SHIPPING CONTAINER FOR BOTTLED MILK AND THE LIKE

Filed Feb. 17, 1923

UNITED STATES PATENT OFFICE.

AUGUST HENDRICH, OF MARTINSVILLE, INDIANA.

THERMOS SHIPPING CONTAINER FOR BOTTLED MILK AND THE LIKE.

Application filed February 17, 1923. Serial No. 619,643.

To all whom it may concern:

Be it known that I, AUGUST HENDRICH, a citizen of the United States, and a resident of Martinsville, county of Morgan and 5 State of Indiana, have invented a certain new and useful Thermos Shipping Container for Bottled Milk and the like; and I do hereby declare that the following is a full, clear, and exact description thereof, reference being had to the accompanying drawings, in which like numerals refer to like parts.

This invention relates to a thermos shipping container for shipping milk in the 15 usual individual quart bottles from dairy to city, such shipments being particularly desirable for certified milk.

The main feature of the invention resides in the construction of a shipping container 20 provided with a plurality of compartments for the reception of milk bottles, whereby they will be fixedly held in position during shipment.

Another feature of the invention resides in 25 the provision of surrounding vacuum chambers or other insulating means, whereby the milk contained therein will be held at a cooling temperature during its transportation.

30 Other features of the invention residing in the construction of the container will be hereinafter more fully disclosed in the appended specifications and claims.

The full nature of the invention will be 35 understood from the accompanying drawings and the following description and claims.

In the drawings, Fig. 1 is a plan view looking down on the container. Fig. 2 is 40 a horizontal section taken through the container showing bottles in dotted lines. Fig. 3 is a section taken on the line 3—3 of Fig. 2. Fig. 4 is an enlarged sectional view of the top portion of the container. Fig. 45 5 is an enlarged sectional view of the bottom portion thereof. Fig. 6 is a vertical section through a portion thereof, showing a modified form.

In the drawings there is shown a container 50 comprising an annular drum-like outer wall 10 formed of a plurality of plies of veneer secured together in the usual manner. About the lower portion of the outer drum-like wall, there is an annular metal band

11 which is secured to an inner band 12 55 by the rivets 13 extending through the wall and joining said bands. The band 12 is provided with a laterally extending flange 14 upon which the bottom 15 of the container rests, said bottom being formed of a 60 plurality of plies of veneer secured together in the same manner as the wall 10. The top 16 is annular in shape and is formed of a plurality of plies of veneer. Said top 16 is hingedly secured over the top of the container by the hinged plate 17 which is attached to the top 16 and engages under the rod 18 secured to the upper edge of the outer wall 10. There is also provided on the 65 lid a hasp and lock 20. Secured to the under side of the lid 16 about the outer edge thereof, there is a yielding pad or gasket 21 adapted to be pressed against the upper edge of the wall 10 so that the same 70 will have a cushioning effect and maintain 75 the drum substantially air-tight when the lid is clamped down in closed position.

The inside of the container is insulated by a plurality of vacuum linings. Supported on the bottom 15, there is a vacuum 80 lining 22 which is comprised of two thin sheet metal walls preferably made of zinc which are separated from each other by a plurality of wires or coils 23 so as to provide a vacuum space 24. After the separating wires have been placed between said walls, they are joined about their periphery so as to prevent air entering therein after the same has been drawn out through the valve 25 by a suitable suction pump for 85 creating a vacuum in the chamber 24. There is a vacuum lining positioned about the walls 10 comprising sheet metal walls 26 inclosing a vacuum chamber 27 from which air may be drawn through the valve 27, 90 said walls 26 being separated by the separating wire 29 inserted in the chamber 27 therebetween. The inner wall 26 is carried up and over the top edge of the wall 10 so as to form a flange 30, as shown in Fig. 4, upon which the pad 21 may rest. The lid 16 is also provided with a vacuum lining 95 comprising the walls 31 which are arranged to enclose the vacuum chamber 32 from which air may be drawn through the valves 33. One of the walls 31 is rigidly secured 100 to the under surface of the top 16 and extends downwardly thereabout, forming the

flange 34 adapted to fit snugly against the inner wall 26. The bottom, top and side vacuum linings abut each other and are tightly fitted together so as to eliminate, so far as possible, the admission of the outside air into the container, whereby the inside of the container may be kept cool for an appreciable length of time; at least sufficient for transportation purposes. The inter-lining 38 is formed of an insulating material which is positioned between the vacuum linings and the inner surface of the outer walls, including the top and bottom so as to further insulate the interior of the container in addition to the insulation effected by the vacuum lining. For further preserving the contents of the container there is provided a valve 39 extending through the bottom and vacuum lining so as to communicate with the interior of the container through which air may be withdrawn, thus producing a vacuum therein completely surrounding the contents. This will have a further temperature retaining effect as well as acting as a further preservative for the contents.

Supported on the bottom lining, there are a plurality of partition walls 35 formed of suitable sheet metal, bent to conform with the shape of the bottles, separating the same and maintaining them in proper position within the container, as shown in Fig. 2. Said partitions extend substantially half way to the top and prevent the bottles being thrown together and thus causing breakage.

Surrounding the wall 10 of the container, there is a band 36 which may be screwed thereon, to which the handles 37 are secured for permitting the container to be readily handled in transportation.

The top or lid 16 has formed thereon an annular ring 40 of an outer diameter slightly less than the inner diameter of the wall 10 so that the containers may be set one upon the other and held in place by reason of the ring 40 fitting into the flanges formed by the wall of the supported container adjacent the bottom thereof.

Fig. 6 shows a modified form of container wherein instead of having a veneer wall 10, the inter-lining 38 is surrounded only by a metal wall 41 held in place and secured by a plurality of reinforcing strips 42 secured to the periphery thereof at the top and bottom and in the center. The handles 37 may be secured to the center band, the lock and hinge may be secured to the top band and the bottom supporting band 12 may be secured to the bottom band.

60 The invention claimed is:

1. A container for shipping milk in individual bottles comprising enclosing walls, sheet metal linings positioned adjacent the inner surface of said walls, sheet metal linings positioned adjacent the first mentioned

linings and spaced therefrom so as to form vacuum chambers, valves associated with said last mentioned linings and communicating with said chambers for permitting air to be drawn therefrom, whereby the interior of the container will be insulated for preserving the temperature therein during transportation, and separating members positioned in said chambers between the linings thereof for holding them apart after the air has been withdrawn.

2. A container for shipping milk in individual bottles comprising an enclosing drum, said drum consisting of an annular wall within which a bottom is supported, and a removable annular top adapted to be secured tightly thereon, a gasket between said top and annular wall for maintaining the container substantially air tight when closed, a vacuum lining positioned about the interior of said annular wall, a vacuum lining positioned on the under side of the top in position to abut the first mentioned lining when the top is closed, a third vacuum lining adjacent the bottom of the container and abutting the first mentioned lining, and members positioned in the vacuum chambers of said linings for separating the walls thereof when the air is withdrawn for producing a vacuum.

3. A container for shipping milk in individual bottles comprising an enclosing drum, said drum consisting of an annular wall within which a bottom is supported, and a removable annular top adapted to be secured tightly thereon, a gasket between said top and annular wall for maintaining the container substantially air tight when closed, a vacuum lining positioned about the interior of said annular wall, a vacuum lining positioned on the under side of the top in position to abut the first mentioned lining when the top is closed, a third vacuum lining adjacent the bottom of the container and abutting the first mentioned lining, members positioned in the vacuum chambers of said linings for separating the walls thereof when the air is withdrawn for producing a vacuum, and valves secured on each of said linings through which the air may be withdrawn for creating a vacuum therein.

4. A container for shipping milk in individual bottles comprising an enclosing drum, said drum consisting of an annular wall within which a bottom is supported, and a removable annular top adapted to be secured tightly thereon, a gasket between said top and annular wall for maintaining the container substantially air tight when closed, a vacuum lining positioned about the interior of said annular wall, a vacuum lining positioned on the under side of the top in position to abut the first mentioned lining when the top is closed, a third vacuum lining adjacent the bottom of the container

and abutting the first mentioned lining, members positioned in the vacuum chambers of said linings for separating the walls thereof when the air is withdrawn for producing a vacuum, valves secured on each of said linings through which the air may be withdrawn for creating a vacuum therein, and

separating walls positioned on said last mentioned vacuum lining for separating the bottles and holding them in position. 10

In witness whereof, I have hereunto affixed my signature.

AUGUST HENDRICH.
